US0D1030865S

(12) **United States Design Patent** (10) **Patent No.:** **US D1,030,865 S**
(45) **Date of Patent:** **** Jun. 11, 2024**

(54) **PEN HOLDER**

(71) Applicant: **Wacom Co., Ltd.**, Kazo (JP)

(72) Inventor: **Naoya Nishizawa**, Toyko (JP)

(73) Assignee: **Wacom Co., Ltd.**, Kazo (JP)

(**) Term: **15 Years**

(21) Appl. No.: **29/819,866**

(22) Filed: **Dec. 17, 2021**

(30) **Foreign Application Priority Data**

Jun. 24, 2021 (JP) ..... 2021-013728 D

(51) **LOC (14) Cl.** **19-06**

(52) **U.S. Cl.**

USPC **D19/81**; D19/99; D14/432

(58) **Field of Classification Search**

USPC D19/77, 81, 82, 84, 85, 136, 178, 192, D19/194, 202, 203, 204, 99; D14/411, D14/432

CPC B43K 23/00; B43K 21/003; B43K 8/00; B43K 7/12; B43K 5/005; B43M 99/008

(57) **CLAIM**

The ornamental design for a pen holder, as shown and described.

DESCRIPTION

FIG. 1 is a rear-top-left perspective view of a pen holder according to my new design;

FIG. 2 is a top-front perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is top plan view thereof; and,

FIG. 8 is a bottom plan view thereof.

The broken lines in the figures depict portions of the pen holder that form no part of the claimed design.

1 Claim, 5 Drawing Sheets
